GAS ENGINE TIMER

Filed July 13, 1920

UNITED STATES PATENT OFFICE.

BYRON E. BOWLES, OF OMAHA, NEBRASKA.

GAS-ENGINE TIMER.

Application filed July 13, 1920. Serial No. 395,888.

To all whom it may concern:

Be it known that BYRON E. BOWLES, a citizen of the United States, residing at Omaha, in the county of Douglas and State 5 of Nebraska, has invented certain new and useful Improvements in Gas-Engine Timers, of which the following is a specification, reference being had therein to the accompanying drawing.

10 The invention relates to timing devices for internal combustion engines, and has for its object to provide a device of this character which will be strong and durable and will be of a wiper type so that the timer will 15 be positive in its operation and short circuits obviated. Also to provide a timer which will not need oiling and will have all of its connections enclosed in a casing, thereby eliminating the common difficulty of oil getting 20 on the wires and causing short circuits.

A further object is to provide a timer comprising a bevelled insulating member carried by the cam shaft said bevelled member being provided with a spring actuated 25 contact member, which contacts with a frusto conically shaped depression in a casting carried insulating member, which frusto conically shaped depressions are provided with flush contact members spaced from each 30 other and adapted to be contacted with by the actuated contact member for making various circuits.

With the above and other objects in view, the invention resides in the combination and 35 arrangement of parts as hereinafter set forth, shown in the drawings, described and claimed, it being understood that changes in the precise embodiment of the invention may be made within the scope of what is 40 claimed without departing from the spirit of the invention.

In the drawings:—

Figure 1 is a side elevation of the timer.

Figure 2 is a vertical longitudinal sectional view through the timer.

Figure 3 is a vertical transverse sectional view taken on line 3—3 of Figure 2.

Figure 4 is a view looking into the disc carrying the contacts showing the same with 50 the cam shaft and distributor removed.

Figure 5 is a front elevation of the distributor.

Referring to the drawings, the numeral 1 designates a cam shaft, to which cam shaft 55 is secured by means of a pin 2, a metallic bushing 3, the rear end of which bushing is

provided with a flange 4. Disposed on the bushing 3 is a distributor 5 formed from insulating material, said distributor is frusto conically shaped and is held in position on 60 the bushing 3 by means of screws 6. Distributor 5 is provided with a cylindrical aperture 7, in which aperture a carbon brush 8 is disposed. Carbon brush 8 is normally held outwardly by means of a coiled spring 65 9. Extending around the distributor 5 is an insulated disc 10, which disc has a centrally disposed aperture 11, through which the bushing 3 and cam shaft 1 extend. Aperture 11 merges into a frusto conically shaped 70 portion 12, the wall of which is angled at the same angle as the periphery of the distributor 5, however the frusto conically shaped portion 12 has its wall slightly spaced from the periphery of the distributor 75 5. Disposed in the disc 10 are contact members 13, which members are threaded so as to allow adjustment outwardly to take up wear, and with which members 13 the carbon brush 8 contacts during the rotation of 80 the cam shaft and distributor 5 so that sparking circuits may be intermittently opened and closed through the threaded contact posts 14, to the outer ends of which posts, wires 15 are connected. Threaded 85 posts 14 also form means for locking and holding the contact members 13 in position, as well as forming means for terminals for the wires 15.

Secured to the outer periphery of the disc 90 10 by means of screws 16 is a casing 17, which casing encloses the structure and protects the same from oil and dirt. The wires 15 pass through the casing 17 as at 18 and through an insulating member 19, which 95 insulating member prevents any possibility of short circuiting in the casing. Extending upwardly from the flange 20 of the casing 17 is an arm 21, to which arm any conventional form of controlling means may 100 be connected for rocking the casing and disc so as to advance or retard the spark.

From the above it will be seen that a timer for internal combustion engines is provided, which timer is positive in its operation and 105 employs the wiper principle of contact thereby eliminating the use of oil and consequent timer troubles, caused by short circuit. Wires 15 lead to battery and the ground is through the cam shaft 1, flange 4 of the 110 bushing 3, spring 9 and carbon brush 8, the timer being adaptable to any ignition sys-

tem, it being understood that the number of contacts may be varied as desired.

The invention having been set forth what is claimed as new and useful is:—

- 5 A timer comprising a frusto conically shaped distributor formed from insulating material, a disc having a frusto conically shaped depression in which the distributor is disposed, a plurality of contact members in the disc and substantially flush with the frusto conically shaped depression therein, means for adjusting said contact members in the disc, set screws for holding said last named contacts in adjusted positions, said
- 10 15 set screws extending angularly into recesses

in the inner ends of the contact members and engaging said contact members to one side of the axis thereof and preventing retrograde movement of the contact members, a spring actuated brush carried by the frusto conically shaped distributor and so positioned that as the distributor rotates it will engage the contact members of the disc, said distributor being carried by a cam shaft, and means for rocking the disc for advancing or retarding the time of contact of the brush and disc carried contacts.

In testimony whereof I hereunto affix my signature.

BYRON E. BOWLES.
